UNITED STATES PATENT OFFICE.

JOHN A. JOHNSON, OF SPOKANE, WASHINGTON, ASSIGNOR OF ONE-HALF TO ADOLPH NELSON, OF HUGO, COLORADO.

TAMPING MACHINE.

Application filed August 17, 1925. Serial No. 50,573.

The present invention relates to improvements in tamping machines for use in laying railway tracks and for repairs in the maintenance of the railway roadbed. The invention contemplates a portable machine of the car-mounted type, which is provided with a motor adapted selectively to propel the machine and to operate its tamping tools. The invention consists in certain novel combinations and arrangements of parts involving the use of two series of tamping tools carried by an oscillatable frame, together with means for reciprocating the frame and its tools transversely of the railway whereby the ties are tamped throughout their full length. Means are also provided for vertically adjusting the frame and its tools, and mechanism is employed for adjusting the extreme outer tamping tools or shovels to accommodate them to ties of various cross sectional dimensions. These and other meritorious features of the invention will hereinafter be more specifically set forth and claimed. In the accompanying drawings I have illustrated one complete example of the physical embodiment of my invention wherein the parts are combined and arranged according to the best mode I have thus far devised for the practical application of the principles of my invention.

Figure 1 is a top plan view of a car-mounted tamping machine embodying my invention.

Figure 2 is a view in side elevation of the machine with the tamping tools shown in dotted line positions.

Figure 3 is an enlarged detail perspective view illustrating one of the tamping tools and a part of the tool frame.

Figure 4 is a top plan view, with parts omitted, as at line 4-4 of Figure 2 showing features of the tool frame, which is partly broken away for convenience of illustration.

In carrying out my invention the machine is mounted on a wheeled truck or car that is adapted to be propelled under power along the railway to the place of construction work, and the truck includes two longitudinally extending side beams 1 and 2 having outwardly offset portions 3 that preferably project beyond the rails R. Four wheels indicated as 4 are provided for the truck or car, two of which are driven from the driving axle 5, and a second axle 6 is provided for the two front wheels which wheels of

course conform to the gage of the railway. A propeller shaft 7 extending longitudinally of the truck is driven from the motor 8 for propelling the truck, and a hand control lever 9 is indicated for controlling the travel 60 of the truck under propulsion.

The tamping machine carried by the truck is selectively driven from the propeller shaft and a clutch lever 10 and clutch 11 on the shaft, together with a worm gear 12, are 65 used to transmit the power of the shaft to a crank gear 13 complementary to the worm gear 12. A pitman 14 connected to the crank gear is used to rock or oscillate the tamping machine as will be described. 70

At the rear and front respectively of the truck, platforms 15 and 16 are fashioned of transversely disposed boards that are secured in suitable manner to the side beams of the truck, for the accommodation of the 75 workmen or construction crew.

Both sides of the ties T are tamped by means of two series of tamping tools or shovels that are supported from a rectangular tool frame that is disposed transversely of the 80 rails and adapted to oscillate or rock upon its longitudinal center to operate the tools.

This tool frame which projects beyond the rails as indicated in Figure 1 is made up of two long side bars 17, two end bars 18 and a 85 series of spaced, intermediate bars 19, all preferably of angle iron and rigidly connected together as will be described.

The cross bars of the tool frame are rigidly secured as by bolts to a transversely arranged channel beam 20 located at the longitudinal center of the frame, and as stated transversely arranged with relation to the rails. This beam and the attached tool frame are adapted to reciprocate transversely 90 of the rails and the beam is adapted to slide on the supporting channel beam 21. As seen in Figure 3 the top channel beam is provided with a pair of spaced slots 22, and the under channel beam 21 is provided with 100 bolts 23 passing through bolt holes in the beam 21 and through the slots in the beam 20. The slotted beam and frame are manually reciprocated on the stationary supporting beam 21 through manipulation of a lever 105 24 pivoted at 24^a and provided with chains 24^b that are anchored to cross bars of the tool frame, one at each side of the transverse center of the frame. It will be apparent that by swinging the lever laterally in 110

Figures 1 and 4 the tool frame and its tools may be reciprocated in order that the tools may tamp the roadbed along both sides of the tie from one end to the other end of the tie.

5 The tamping action of the tools is caused by an oscillating or rocking motion imparted to the tool frame from the pitman 14, and for this purpose the beam 21 is fitted over a 10 rock shaft 25 extending transversely of the rails and provided with end bearings 26 which bearings are bolted rigidly to the end bars 18 of the frame.

15 The rock shaft is located within a pair of inverted U-shaped brackets 27 spaced apart and bolted on top of the offset portions 3 of the side beams of the truck. As best seen in Figure 4 the brackets are each provided with a pair of opposed vertical grooves 28, 20 and within each bracket the rock shaft is provided with a loose sleeve or collar 29 having a pair of outwardly extending, vertical plates or wings 30 that are guided in the complementary grooves 28 of the brackets.

25 The sleeves, loose on the shaft, are thus non-rotatable, but move vertically with the shaft when the frame is lowered or raised. The tool frame and its tools may be elevated to inoperative position when not required for 30 use and while the machine is traveling, or the tool frame may be adjusted vertically to bring the tamping tools at various heights along the sides of the tie to be tamped. For vertically adjusting the frame and two series 35 of tools an operating lever 31 which is connected by a cable 32, is utilized. This lever, as is also the lever 24, is pivoted on a cross brace A which rigidly connects the two brackets 27, as best seen in Figure 1. As 40 seen in Figure 2 a crank arm 33 depends from the underside of the rock shaft, and the pitman 14 is pivotally connected thereto at 34 for oscillating the tool frame and tools as indicated by dotted lines in Figure 2.

45 I preferably employ two series of tamping tools or shovels indicated by the numerals 35 and 36, one at each side of the tie T and spaced at regular intervals along the opposite sides of the tool frame. The tools are 50 preferably of metal with flat blades that extend transversely of the rails, and each blade is provided with a flat shank 37 which may be fashioned by twisting it to a plane at right angles to the plane of the blade or shovel. The tamping tools are carried by 55 the several spaced cross bars of the tool frame, and the shanks of the tools are adjustable with relation to these cross bars. For this purpose the vertical flanges of the 60 cross bars are provided with slots 38 near their ends, and retaining bolts 39 are passed through bolt holes in the shanks and through the slots, and clamping nuts 39' are used to clamp the shank against the flange of the 65 cross bar. The tools may thus be adjusted

toward or away from the longitudinal center of the transversely arranged tool frame and adjusted in the same relation to the tie to be tamped.

70 The two side bars of the tool frame are also adjustable toward and away from the longitudinal center of the tool frame to adapt these bars to the adjusted shanks of the tools for supporting the shanks. For 75 this purpose the horizontal flanges of the angle iron cross bars are slotted as at 40 near their respective ends, and clamping bolts 41 are passed through bolt holes in the side bars and through the slots of the cross bars. The shanks of the tools are thus supported within an angle formed by the side bars and cross bars of the tool frame, and the tools are maintained in proper position for tamping when the tool frame is rocked or oscillated.

80 Frequently the ends of a tie are of less cross sectional area than the body of the tie, i. e. the ends are smaller than the body, or either one of the ends may be smaller than the body of the tie. To adapt the two 85 end pairs of tamping tools to the smaller part of the tie, these tools may be drawn in toward the tie for tamping it. For this purpose the lever 24 is provided with a pair of radius rods 42 that extend outwardly 90 from the longitudinal center of the tool frame and at their outer ends the rods are provided with connecting plates 43 from which radiate pivoted links 44 that are pivoted to the two end pairs of tamping tools. 95 As the lever 24 is swung to reciprocate the tool frame and tools transversely of the rails it will be apparent that these end tamping tools are moved toward and away from the tie in addition to the rocking movement 100 that is applied to the tool frame for operating the tools.

105 As the tamping continues during the mechanical operation of machine the tools may be gradually elevated, by manual means, 110 with relation to the tie being tamped to accommodate the material being fed or shoveled into the bed at both sides of the tie. The lateral reciprocation of the frame and tools may be controlled with facility by 115 manipulating the hand lever 24, and after one tie has been properly tamped the truck may be moved to position with the tamping frame over an adjacent tie for a repetition 120 of the tamping operation.

125 Having thus fully described my invention what I claim as new and desire to secure by Letters Patent is—

1. In a tamping machine the combination, with a tool frame and tamping tools suspended therefrom, of means for rocking said frame, means for laterally reciprocating said frame and tools, and means for vertically adjusting said frame and tools.

2. In a tamping machine the combination

with a tool frame having a rigid longitudinal central beam, of a supporting beam upon which said central beam is slidable, a rock shaft beneath the supporting beam, and means for rocking said frame.

3. In a tamping machine the combination with a main frame and a pair of spaced brackets thereon, of a shaft, nonrotatable sleeves on said shaft and guides on said sleeves co-acting with said brackets, a tool frame and means for supporting said shaft from said frame, and means for rocking said frame in said sleeves.

4. In a tamping machine the combination with a main frame and a pair of spaced brackets thereon, of a shaft, non-rotatable bearing sleeves on said shaft having guide plates engaging grooves in said bracket, a tool frame supported on said shaft, means for rocking said frame, and means for vertically adjusting said frame and shaft.

5. The combination with a supporting

beam and a beam supported to reciprocate thereon, of a tool frame rigid with said reciprocal beam, means for moving said frame on the supporting beams, and means for simultaneously oscillating said tool frame.

6. The combination with a supporting beam, of a slotted reciprocal beam thereon having a bolt connection therewith, a tool frame rigid with the slotted beam, means for reciprocating the tool frame, and means for oscillating said frame.

7. In a tamping machine the combination with a tool frame and tamping tools suspended therefrom, of means for rocking said frame means for laterally reciprocating said frame and tools, means for vertically adjusting said frame and tools, and means for relatively adjusting end pairs of tools as described.

In testimony whereof I affix my signature.

JOHN A. JOHNSON.
